UNITED STATES PATENT OFFICE.

WILLIAM F. NORMAN, OF NEVADA, MISSOURI.

ARCHED METAL GRAVE-BOX COVER.

Application filed October 23, 1925. Serial No. 64,357.

This invention relates to improvements in metallic grave box covers, one object of the invention being the provision of a sheet metal sectional cover hinged centrally of its length, so that when it is positioned in the dug grave above the box, the earth filled in on the cover will tend to project and hold the edges of the cover projected into the solid earth, so that the cover will be properly supported above the box to prevent the earth from reaching the box and also the top of the grave from sinking at the surface.

Another object of this invention is the provision of a grave box cover, made of a plurality of curved corrugated sheets of galvanized metal, and provided with a hinging element upon the inner edge of each section or sheet, so that the sheets when in shipment or being stored can be nested or placed in packs, and which are easily and quickly assembled at the grave for use.

In the accompanying drawings:—

Figure 1 is a sectional view through a grave showing the present cover in section and place with the box in elevation.

Figure 2 is a similar view with earth filled in and showing the effect of such weight upon the cover.

Figure 3 is a top plan view of two sheets, comprising one section showing how the two sheets are slid together at the hinge.

Referring to the drawings, the numeral 5 designates the grave opening, 6 the grave box, and 7 the side walls, which are here shown as being provided each with a shoulder 8, a short distance above the top of the box.

The present cover 9, is composed of a number of sections 10, each one of which is composed of two curved sheets 11 and 12, preferably corrugated and made rust resistant by galvanizing, and upon the inner edge of the sheet 11 is provided with female portion 13 of the central hinge of the two sections.

The cooperating edge of the sheet 12 is provided with the male portion 14 of the hinge, and these portions are so formed as to permit the female portion 14 to slide longitudinally over and encase the male portion 13 as shown in Figure 3, and thus when the sheets are hinged together to form a section, a water tight joint at the hinge is provided, and yet permit sufficient hinging movement between the sheets for carrying out the objects of this invention.

The earth engaging edges 15 and 16, respectively of the sheets 11 and 12, are adapted to rest on the shoulders or ledges 8, just above the grave box as shown in Figure 1, so that when the earth is filled in upon the cover, the weight thereof will slightly depress the sections at the hinge and force the edges outwardly and more firmly into the earth of the side walls. In this manner the cover is held more firmly in place and gives better protection to the box and, as the distance of depression at the hinge is limited, the earth at the top is held against sinking in.

By the use of the hinge the grave cover is made adaptable and adjustable to various widths of graves, and by being made in sections various lengths of grave may also be taken care of without employing various widths and lengths of covers.

What I claim as new, is:—

A sectional arched sheet metal grave cover, each section of which is composed of two members, one of the members being provided with a female hinging portion on one edge the full length thereof while the other member is provided with a similarly shaped male hinging portion the full length of one edge thereof for the reception within the female member to provide a water tight and adjustable means for the section.

In testimony whereof I affix my signature.

WILLIAM F. NORMAN.
